UNITED STATES PATENT OFFICE.

THOMAS HENRY WHELESS, OF NEW YORK, N. Y.

SUBMERGIBLE SURFACE BOAT.

No. 806,223.

Specification of Letters Patent.

Patented Dec. 5, 1905.

Application filed May 31, 1905. Serial No. 263,079.

To all whom it may concern:

Be it known that I, THOMAS HENRY WHELESS, a citizen of the United States, residing at New York city, in the borough of Manhattan and State of New York, have invented certain new and useful Improvements in Submersible Surface Boats; and I do hereby declare the following to be a full, clear, and exact description of the invention, such as will 10 enable others skilled in the art to which it appertains to make and use the same.

My invention relates to submersible surface boats; and it is intended more especially to relate to boats having very fine lines with deep 15 draft and narrow beam, which are intended to have very little free-board, which will run very fast along the surface of the water and may be readily submerged when desired, and which will run at high speed when submerged. 20 My invention will be understood by reference to the accompanying drawings, in which the same parts are indicated by the same letters throughout the several views.

Figure 1 represents a side elevation of the 25 preferred form of boat. Fig. 2 is a plan view of the device shown in Fig. 1. Figs. 3, 4, 5, and 6 show the contours of the cross-sections along the lines 3 3, 4 4, 5 5, and 6 6, respectively, of Fig. 2. Fig. 7 shows a side elevation of a slightly-modified form of boat. Fig. 8 is a plan of the device shown in Fig. 7, and Figs. 9, 10, 11, and 12 indicate the contours 30 of the cross-sections made by the lines 9 9, 10 10, 11 11, and 12 12, respectively, of Fig. 8.

Referring first to Figs. 1 to 6, A represents the waist portion of the boat, B the bow portion, and C the overhanging stern portion, the cross-sections of the various portions being indicated in Figs. 3 to 6, respectively.

40 D represents a conning-tower which is located above the waist portion and is preferably elongated in form and curved fore and aft, as at d, provided with bulls'-eyes d' and with manholes and covers d''.

45 I represents the deck, which is slightly curved upward toward the midship-section and tapers fore and aft downward, terminating at practically the water-line w w when the boat is properly trimmed and loaded for 50 cruising.

E represents a screw-propeller which is driven by any suitable engine low down in the waist of the boat.

F represents the steering-rudder, and G the 55 diving-rudders. The propelling mechanism

and the steering and diving mechanism may be of any preferred form and are not a part of my present invention.

The lower part of the waist portion of the boat is weighted, which may be either accomplished by making this part in the form of a wedge-shaped solid keel, as shown in Fig. 5, or this keel may be supplemented by or replaced by removable weights. Such keel is indicated at H of Figs. 1 and 5.

60 Referring now to the form of boat shown in Figs. 7 to 12, there is a long and sharp bow portion B', a deep, sharp, and narrow waist portion A', and a comparatively shallow and broad stern portion C'. The keel or weights 65 H and the other parts of the device are substantially the same as have been described with reference to Figs. 1 to 6.

The form of boat shown in Figs. 7 to 12 has substantially the same under body as is 75 described and claimed in my application entitled "Improvement in the construction of vessels," filed October 14, 1903, Serial No. 177,031; but the superstructure is so changed 80 as to adapt the boat to be submerged when desired.

It will be seen that in all the forms of construction herein shown the boat has exceedingly fine lines, with very narrow beam and great depth in the waist, and that the weights 85 are carried at the lower part of this waist portion, thus giving the boat great stability, and this position of the weights near the center tends to permit the boat to be turned readily about the center in diving or rising. Furthermore, 90 the sharp wedge-shaped bow not only permits the boat to speed very fast through the water when either awash or submerged, but also reduces the resistance to diving when the diving-rudders are set for diving. Furthermore, 95 the shape of the boat enables it to cut through the waves, and thus limits pitching, while the disposition of the weights in the waist portion insure great stability in a cross sea.

100 It will be noted that the line of greatest buoyancy of the boat is very high up, owing to the flaring shape of the cross-sections throughout, the greatest beam of any cross-section being practically at the deck-line. Thus by having the buoyancy well up and the 105 weights well down great stability is secured and the boat even if rolled over by a sea will immediately resume the upright position.

It will be seen that the maximum draft of 110

the waist portion, including the body of the hull, but excluding any exterior keel, (not shown,) is in excess of the maximum beam of said waist at the water-line. In the drawings 5 this proportion is shown as about two to one; but these proportions may be varied so long as the depth is maintained in excess of the beam. As was explained in my application Serial No. 177,031, the state of the art shows 10 that the object aimed at was to secure a boat that would skim along the surface of the water and in which the motive power tended to force the boat upward the faster it traveled. Such boats have small draft compared to their 15 maximum beam at the water-line, and the necessary stability is secured by added fin or bulb keels. The object of my invention is to provide a boat which will cut through the water and will not tend to skim along the surface of 20 the water at all and in which the waist-section is made very deep and sharp, so that the machinery and weights may be placed low down inside of the hull proper. Furthermore, by having the machinery placed low down the 25 propeller-shaft may be installed in a horizontal position, so that any tendency of the propeller to lift the stern due to an inclined propeller-shaft may be obviated and also the driving thrust of the propeller may be more 30 efficient. Moreover, by having the propeller at some distance below the surface of the water it acts on the water under pressure and diminishes the slip.

By having the boat of deep draft in the 35 waist portion not only is it possible to have the weights located deep down below the line of flotation, thus increasing the metacentric height, but this construction also affords suitable space for installing the engines and for 40 the convenience of the crew.

Finally, by having the boat running practically awash and with an extremely narrow beam she could with difficulty be observed by an enemy, and, if observed, it would be difficult to strike with a projectile.

Having thus described my invention, what I claim, and desire to secure by Letters Patent of the United States, is—

1. A marine vessel adapted to run along the 50 surface of the water or to be submerged when desired, comprising a sharp and narrow fore body, a narrow waist deeper than the beam, and a shallow overhanging stern portion, all the contours of the hull of the boat being continuous curves, and the maximum width of each cross-section being at the top of the sides, substantially as described.

2. A marine vessel adapted to run along the 60 surface of the water or to be submerged when desired, comprising a sharp and narrow fore body, a narrow waist deeper than the beam, and a shallow overhanging stern portion, all the contours of the hull of the boat being continuous curves, and the maximum width of

each cross-section being at the top of the sides, 65 and the lower portion of the waist being weighted, substantially as described.

3. A marine vessel adapted to run along the surface of the water or to be submerged when desired, comprising a sharp and narrow fore 70 body, a narrow waist deeper than the beam, and a shallow overhanging stern portion, all the contours of the hull of the boat being continuous, and the maximum width of each cross-section being at the deck-line, with a deck tapering slightly downward toward the bow and stern, substantially as described.

4. A marine vessel adapted to run along the surface of the water or to be submerged when desired, comprising a sharp and narrow fore 80 body, a narrow waist deeper than the beam, and a shallow overhanging stern portion, all the contours of the hull of the boat being continuous curves, the lower portion of said waist being weighted, and the maximum width of 85 each cross-section being at the deck-line, with a deck tapering slightly downward toward the bow and stern, and an elongated conning-tower mounted in the deck above the waist portion, substantially as described.

5. A marine vessel adapted to run along the surface of the water or to be submerged when desired, comprising a sharp and narrow fore body merging into a narrow waist deeper than the beam, the latter curving up rapidly into a 95 shallow overhanging stern portion, all the contours of the hull of the boat being continuous curves, and the lower portion of said waist being weighted, substantially as described.

6. A marine vessel adapted to run along the 100 surface of the water or to be submerged when desired, comprising a sharp and narrow fore body merging into a narrow waist deeper than the beam, the latter curving rapidly into a 105 shallow overhanging stern portion, all the contours of the hull of the boat being continuous curves, and the lower portion of said waist being weighted, with a deck tapering slightly downward toward the bow and stern, substantially as described.

7. A marine vessel adapted to run along the surface of the water or to be submerged when desired, comprising a sharp and narrow fore body merging into a narrow waist deeper than the beam, the latter curving rapidly into a 115 shallow overhanging stern portion, all the contours of the hull of the boat being continuous curves, and the lower portion of said waist being weighted, and each cross-section of the hull having its greatest width at the 120 top of the sides, substantially as described.

8. A marine vessel adapted to run along the surface of the water or to be submerged when desired, comprising a sharp and narrow fore body deeper than the beam and wedge-shaped 125 in vertical cross-section, the said fore body merging obliquely downward into a deep and narrow waist also wedge-shaped in vertical

cross-section and deeper than the beam, and a shallow overhanging stern portion, all the contour-lines of the hull of the boat being continuous curves, substantially as described.

5 9. A marine vessel adapted to run along the surface of the water or to be submerged when desired, comprising a sharp and narrow fore body deeper than the beam and wedge-shaped in vertical cross-section, the said fore body merging obliquely downward into a deep and narrow waist also wedge-shaped in vertical cross-section and deeper than the beam, and a shallow overhanging stern portion, all the contour-lines of the hull of the boat being continuous curves, and the lower portion of said waist being weighted, substantially as described.

10. A marine vessel comprising a wedge-shaped sharp and narrow fore body, a deep and narrow waist, the draft of which to the bottom of the hull proper is greater than the maximum breadth of beam of said waist, and a shallow overhanging stern portion, substantially as described.

25 11. A marine vessel comprising a wedge-shaped sharp and narrow fore body, a deep and narrow waist, the draft of which to the bottom of the hull proper is greater than the maximum breadth of beam of said waist, and a shallow overhanging stern portion, all the contours of the hull of the boat being con-

tinuous curves, and the lower portion of said waist being weighted, substantially as described.

12. A marine vessel comprising a wedge-shaped sharp and narrow fore body, a deep and narrow waist, the draft of which to the bottom of the hull proper is greater than the maximum breadth of beam of said waist, and a shallow overhanging stern portion, all the contours of the hull of the boat being continuous curves, and the lower portion of said waist being weighted, with an arched deck, substantially as described.

13. A marine vessel adapted to run along the surface of the water or to be submerged when desired, comprising a wedge-shaped sharp and narrow fore body, a deep and narrow waist, the draft of which to the bottom of the hull proper is greater than the maximum breadth of beam of said waist, and a shallow overhanging stern portion, the lower portion of said waist being weighted, with a deck tapering slightly downward toward the bow and stern, substantially as described.

In testimony whereof I affix my signature in presence of two witnesses.
